Primary Examiner — George D. Kirschbaum

Assistant Examiner — Patricia K. Beard

(74) Attorney, Agent, or Firm — Howard & Howard
Attorneys PLLC(57) **CLAIM**

The ornamental design for a toy magnetic tile, as shown and described.

DESCRIPTION

FIG. 1 is a top, front, right-side, perspective view of a toy magnetic tile;

FIG. 2 is a top view thereof;

FIG. 3 is a bottom view thereof;

FIG. 4 is a rear view thereof;

FIG. 5 is a front view thereof;

FIG. 6 is a left-side view thereof; and,

FIG. 7 is right-side view thereof.

The broken lines in the drawings depict portions of the toy magnetic tile that form no part of the claimed design.
